FREDERICK W. LYLE, OF LYNN, AND JAMES N. TUTTLE, OF BOSTON, MASSACHUSETTS,
ASSIGNORS TO BEACON ACCESSORIES CORPORATION, A CORPORATION OF MASSA-
CHUSETTS.

REFLECTOR FOR USE IN HEADLIGHTS.

Application filed August 15, 1916. Serial No. 115,009.

To all whom it may concern:

Be it known that we, FREDERICK W. LYLE, a citizen of the United States, residing at Lynn, in the county of Essex, in the State 5 of Massachusetts, and JAMES N. TUTTLE, a citizen of the United States, residing at Boston, in the county of Suffolk, in the State of Massachusetts, have jointly invented a new and useful Improvement in Reflectors 10 for Use in Headlights, of which the following is a specification, reference being had to the accompanying drawings.

The object of this invention is to provide a headlight for vehicles from which 15 there shall be no objectionable glare in the eyes of approaching pedestrians or drivers.

This is accomplished by so shaping the reflector that the glaring rays of light are wholly confined to space below a certain pre- 20 determined level.

In Figure 1 of the attached drawing such a headlight is shown mounted in the usual position on an automobile, the projected rays of light being represented by dotted lines. 25 Figure 2 shows a vertical, longitudinal, mid-section of this headlight. Figure 3 shows a front view.

In Figures 2 and 3 the letter *a* denotes the casing of such a headlight, the letter *b* the reflector and the letter *c* an electric light bulb, located near the focal point thereof. The light source is preferably located forwardly of at least the focus of the upper 30 half of the reflector, and in Fig. 2 we have illustrated the two foci as being coincidentally disposed at *f* immediately in the rear of the light source.

Heretofore headlight reflectors have been formed as surfaces of revolution, ordinarily 40 hyperboloids or paraboloids, about an axial line, such a line constituting an axis of symmetry therefor. In practice the headlights are so mounted that their axis is substantially horizontal; furthermore, the light 45 beam forms a cone, the marginal rays of which diverge at a considerable angle from the axis. It therefore comes about that the light constituting the upper half of this cone is thrown upward at so great an angle 50 that it is not only lost but it produces a blinding glare in the eyes of approaching pedestrians or drivers of vehicles. This objectionable effect we eliminate by forming the reflectors of the headlights as described 55 below.

Ordinarily the light source is so located with respect to the reflector that the objectionable light constituting the upper portion of the conical beam emanates from the lower half of the reflector, that is, the light source is usually positioned in front of the focus. We therefore form the reflector of what might be considered two segments, an upper and a lower, the axis of the upper segment being substantially horizontal and the axis of the lower being inclined forward and downward with respect to the axis of the upper segment. In Figure 2 and Figure 3 such a reflector is shown. In Figure 2 the letter *b* denotes the upper segment, the axis 60 of which is *e-f*; and the letter *d* denotes the lower half, the axis of which is *e-g*.

In such a reflector the light from the bulb, when properly focused, is reflected in the form of a cone of light as shown in detail by 70 the dotted lines *o-k-l* and *o-m-n* of Figure 2. The axis of the upper segment being horizontal and the lamp focused as above described, the rays *o-k-l* reflected by it are thrown out, some horizontally and others slightly tipped downward as shown. If the axis of the lower segment were also horizontal it would reflect rays forward and upward. It is however tipped downward at 75 such an angle as to throw light forward and downward only, as indicated by the dotted lines *o-m-n*. Thus no rays emanating from either segment of the reflector rise above the level of the headlight. The general appearance of the light beam is indicated by the dotted lines of Figure 1.

The attainment of this result may, of course, be brought about either by combining the two segments integrally in a single reflector or by making the lower segment 80 separate from the upper and placing it in the above described position with reference thereto. The glare from a reflector of the kind now commonly used may therefore be eliminated by attaching within it a segment 85 of a surface of revolution so as to cover its lower half and so placed that it shall take up a position, with reference to the light source and the upper segment, similar to that of the lower segment above described.

From the above description it will be apparent that the present invention is intended to be applied to headlights in which the light source is disposed substantially in the focus or forwardly of the focus of the re- 100 105 110

reflector. With the light source so disposed substantially all light striking the upper half of the reflector is reflected in or below a horizontal direction and, in the absence of our invention, substantially all light striking the lower half of the reflector would be reflected in and above a horizontal direction in such manner as to produce upward glare. However, with the lower reflector orientated 10 downwardly about a transverse axis passing through the region of the light source and focus, the beam produced by the lower half of the reflector, part of which is ordinarily projected upwardly, is swung downwardly, 15 and by orientating the lower half through a suitable angle the beam produced thereby can be swung substantially wholly below the horizontal plane through the light source. The lower half of the reflector may be disposed 20 in such angular relationship to the upper half that the light therefrom is directed to the nearer portions of the roadway. However, we prefer to arrange the two reflectors so that the angle between the axes is 25 relatively small, and so that the light from the lower half of the reflector is directed into substantially the same space as the light from the upper half, thereby not only eliminating upward glare but also intensifying 30 the illumination of the roadway.

Instead of true paraboloidal reflectors we may use reflectors having other contours, such as that of a hyperboloid, and indeed we preferably use a hyperboloidal contour 35 differing slightly from a paraboloidal contour so that light is reflected from each half reflector in the form of a half cone, thereby to secure better distribution of light throughout near and distant portions of the roadway 40 and along the sides of the roadway. However, the cardinal features of the invention comprise the orientated position of the lower half reflector relatively to the upper half and the orientation of the lower half substantially about a transverse axis through 45 the region of the light source and focus.

In the appended claims the expressions horizontally, upwardly downwardly, etc. are used merely in a relative sense in order more 50 conveniently to refer to relative positions, and these terms are not to be construed as necessarily being employed with reference to the earth's surface. The word "axis" is employed to signify a line of symmetry of a 55 reflector and is not intended to refer solely to the major axis of a surface of revolution. On the contrary it is intended also to apply to the central axis of a surface which has a 60 cross-sectional contour other than circular as, for example, an elliptical contour.

Having thus described our invention, we claim as new and wish to secure by Letters Patent:

1. In light projection apparatus for projecting a concentrated beam of light hori-

zontally without producing appreciable upward glare, the combination of a light source, an upper reflecting surface adapted to project a concentrated beam of light along its axis, the upper surface being disposed 70 predominantly above the horizontal plane of the light source with its focus in the region of the light source and its axis disposed substantially horizontally, so as to project light substantially horizontally without projecting appreciable light upwardly, and a lower reflecting surface disposed predominantly below said horizontal plane with its focus in the region of the light source and its axis directed downwardly, so as to project light downwardly without projecting light upwardly, said surfaces meeting in the region of the horizontal plane passing through the light source.

2. In light projection apparatus for projecting a concentrated beam of light horizontally without producing appreciable upward glare, the combination of upper and lower reflecting surfaces adapted respectively to project beams of light along their 80 axes, the reflecting surfaces being arranged in opposition with their foci coincident, and a light source disposed in the focal region of the reflecting surfaces, the upper reflecting surface having its axis disposed substantially horizontally and the lower reflecting surface having its axis directed downwardly, and the light source being so disposed with 90 relation to the respective foci that light is projected in and below a horizontal direction without projecting substantially any light upwardly, said surfaces meeting in the region of the horizontal plane passing through the light source.

3. In light projection apparatus for projecting a concentrated beam of light longitudinally without producing appreciable upward glare, the combination of upper and lower reflecting surfaces adapted respectively to project beams of light along their axes, 105 the reflecting surfaces being arranged in opposition with their foci approximately coincident, and a light source disposed in the focal region of the reflecting surfaces, the upper reflecting surface having its axis disposed substantially horizontally and the lower reflecting surface having its axis orientated downwardly with respect to the other axis about a transverse axis passing 110 through the focal region.

4. In light projection apparatus for projecting a concentrated beam of light longitudinally without producing appreciable upward glare, the combination of upper and lower reflecting surfaces adapted respectively to project light predominantly along their axes, the reflecting surfaces being arranged in opposition with their foci approximately coincident, and a light source disposed in the focal region of the reflecting surfaces, the 125 130

upper reflecting surface having its axis disposed substantially horizontally and the lower reflecting surface having its axis orientated downwardly with respect to the other axis about a transverse axis passing through the focal region, and the light source being so disposed with relation to the

respective foci, forwardly of the focus of the upper reflecting surface, that light is projected in and below a horizontal direction ¹⁰ without projecting substantially any light upwardly.
